UNITED STATES PATENT OFFICE

2,150,614

SMOKE DESTROYER

Alexander Sutkowski, St. Louis, Mo.

Application April 12, 1937, Serial No. 136,493

2 Claims. (Cl. 261—123)

This invention relates to a gas cleaning or washing device and pertains particularly to a device of this character designed primarily for use in association with furnaces or similar structures which discharge gases into the atmosphere.

The present invention has for its primary object to provide a washer mechanism which when interposed between the chimney outlet of a furnace and the outside atmosphere, will remove from the smoke issuing from the furnace, all fly ash and soot particles which go to form smoke, and also neutralize acid-forming fumes before the same are discharged from the atmosphere vents of the heating system.

Another object of the invention is to provide a smoke washing mechanism which is so designed that it may be economically constructed and which is inexpensive to keep in operation.

The invention will be best understood from a consideration of the following detailed description taken in connection with the accompanying drawing forming part of this specification, with the understanding, however, that the invention is not confined to any strict conformity with the showing of the drawing but may be changed or modified so long as such changes or modifications mark no material departure from the salient features of the invention as expressed in the appended claims.

In the drawing:

Figure 1 is a view in top plan of the mechanism embodying the present invention showing the same coupled to a furnace.

Fig. 2 is a view in side elevation of the structure, the parts being broken away to show interior constructional details.

Referring now more particularly to the drawing the numeral 1 generally designates the body of the smoke washer which comprises a casing, here illustrated as being of rectangular horizontal cross-section, but it is to be understood that a casing of any suitable design may be employed. This rectangular casing which is here shown as preferably mounted upon the supporting base structure 2 has in addition to the vertical side walls 3 and bottom wall 4, the top 5 which is in the form of a removable plate secured by the bolts 6 to the flange collar 7 which is attached to the side walls of the casing at the top.

One of the side walls of the casing is preferably provided with a suitable clean-out opening 8 and with a vertically disposed liquid level gauge class 9 of standard type for the purpose herein-after described.

Mounted upon the top 5 is a blower 10 of

suitable design, having the outlet 11 thereof secured to a downwardly extending pipe 12 which passes through the top 5 of the casing and a substantial distance downwardly in the casing. This fan structure 10 is preferably of a motor driven type, and there is therefore provided a motor 13 coupled through the shaft 14 with the rotatably mounted blades of the fan (not shown) so that a suitable air blast may be created in the pipe 12 for the purpose hereinafter described.

The inlet of the fan 10, which is indicated at 15, has coupled therewith the conduit 16 which leads from the smoke outlet opening 17 of the furnace structure, a portion of which is shown, and indicated by the numeral 18. Within this conduit 16 is interposed a suitable T-coupling 19, the angle of which is directed downwardly and has removably attached thereto the removable soot collecting receptacle 20. Any suitable means may be employed for attaching the receptacle 20 to the angle 19, but there is here illustrated a pivoted hook 21 which is designed to engage over a suitable pin 22 forming a part of the T-shaped union. The angular extension of the union extends into the open top of the soot receptacle, as illustrated.

The fan or blower 10 is preferably disposed adjacent one corner of the casing 1 and at the opposite corner there is secured the gas lead-off or flue pipe 23, a portion of which is vertically disposed, as illustrated. Suitably supported in the center of the opening formed through the top 5 and over which the inlet end of the flue pipe 23 is positioned, is a condensate return pipe 24 which is disposed to extend axially of the vertical portion of the flue pipe and projects downwardly a substantial distance into the casing 1. At its upper end the pipe 24 has an integral funnel-like receiver 25 and below this a pair or more of funnel-like collars 26 which surround the pipe. Within the area circumscribed by the collars 26 the pipe is provided with one or more apertures so that moisture collected by the collars will flow through these apertures which are indicated by the numeral 27, into the pipe 24. The collars 26 and the funnel-like upper end part 25 of the pipe are of progressively decreasing circumference and secured within the flue pipe 23 above the funnel 25 is a funnel-like baffle 28, the periphery of which is attached to the inside of the pipe 23, while the center is open and is disposed directly above the upper end of the pipe 24.

Disposed horizontally within the casing 1 is a plate 29 through which the pipes 12 and 24 pass.

These pipes are secured to this plate and support the same in the casing. The plate 29 is provided with the integral downturned flange 30 which is in spaced relation with the walls 3 of the casing 5 so as to provide the passageways 31. Secured to and extending through the plate 29 is a series of short gas tubes 32 which project above and below the plate, as illustrated. However, the lower ends of these tubes 32 do not extend down to the horizontal plane of the edge of the flange 30, and this applies also to the lower end of the pipe 12 which extends only a distance as required for a "rolled" connection. The pipe 24, however, extends downwardly in the casing a substantial distance below the edge of the flange 30, as illustrated.

When the present device is in service, the casing 1 is filled with a suitable alkaline solution to a level well above the top ends of the gas tubes 32, and the gauge 9 will be so disposed as to indicate the level of this liquid. With the soot receptacle 20 in position and the flue pipe 23 connected with a suitable chimney outlet the smoke conduit 16 is connected with the furnace 25 outlet and the smoke from the furnace will be drawn thru the conduit and driven by the fan 10, downwardly through the pipe 12 to discharge into the liquid in the casing, below the tube plate 29. Any heavy soot particles passing 30 through the conduit will drop into the soot receptacle 20 and the lighter soot particles will be driven into the neutralizing fluid in the casing where they will sink to the bottom and where also the acid forming substances in the furnace 35 gases will be neutralized. The gases and air driven by the fan 10 below the plate 29 and its flange 30 forms until a sufficient quantity has collected to force the liquid down so that the gases will escape through the tubes 32. They 40 will then, of course, pass upwardly thru the liquid in the tubes causing an "air lift" action on the fluid in the tubes causing upward circulation of liquid and pass outwardly through the flue pipes 23. The annular passageway 31 provides a path 45 for the downward return of liquid to the lower side of dished plate. The escaping gases will naturally carry a considerable amount of moisture as they pass through the pipe 23, and a great deal of this will be condensed by bringing 50 the gas into contact with the baffle plate 28 and with the baffle collars 26, and this condensate will flow back through the pipe 24 into the lower part of the receptacle.

From the foregoing it will be readily apparent 55 that a device of the character herein described when attached to the gas outlet of a furnace, will operate efficiently to remove soot and like ash particles from the furnace gases, and will also neutralize the acid forming fumes com-

monly found in such gases so that the final gas which is discharged into the atmosphere will have a neutral reaction and will be clean.

What is claimed, is:

1. A furnace attachment of the character described, comprising a closed receptacle, a furnace gas conducting conduit leading downwardly into the receptacle to a point adjacent the bottom thereof, the inlet end of the conduit being designed for attachment to a furnace gas outlet, a flue pipe outlet leading from the top of the receptacle, a plate disposed horizontally within the receptacle and having the outlet end of said gas conduit secured thereto and opening to the underside of said plate, a plurality of vertically disposed short gas tubes passing through and extending above and below said partitioning plate, the lower ends of said tubes extending below the outlet end of said gas conduit, a flange 5 extending downwardly from and completely encircling the edge of said partitioning plate and having spaced relation with the sides of the enclosing receptacle, said flange having its lower edge in a plane below the lower ends of said tubes, and a neutralizing liquid filling the receptacle to a level above the plane of the upper ends of said tubes.

2. A gas washer of the character described, comprising a receptacle having a removable top, a gas inlet pipe secured to and extending through 30 said top and having the inner discharge end thereof terminating in the lower part of the receptacle, a washed gas outlet pipe carried by and opening through said top, a plate member disposed horizontally within the lower part of 35 the receptacle and having a relatively wide downwardly extending surrounding flange, said flange being in spaced relation throughout with the walls of the receptacle and said plate having an opening therethrough in which the lower end 40 of the gas inlet pipe is secured, said gas inlet pipe constituting a supporting means for the plate at one side thereof, supporting means connecting the plate at the opposite side from the inlet pipe with said top, a plurality of short tubes 45 extending through said plate and having their upper ends extended above the top surface of the plate and their lower ends extended downwardly below the lower surface of the plate but terminating short of the plane of the lower edge of said flange, said receptacle being designed to be filled with a neutralizing solution to a level above the upper ends of said tubes, and said discharge end of said gas inlet pipe being above the plane of the lower ends of said tubes whereby 50 gas discharged beneath the plate from said inlet pipe will collect in a body across the underside of the plate.

ALEXANDER SUTKOWSKI.
